UNITED STATES PATENT OFFICE.

GEORGE J. LEBER, OF CLEVELAND, OHIO.

WASHLINE REEL.

Application filed July 15, 1921. Serial No. 484,916.

To all whom it may concern:

Be it known that I, GEORGE J. LEBER, a citizen of the United States of America, residing at Cleveland, in the county of Cuyahoga and State of Ohio, have invented certain new and useful Improvements in Washline Reels; and I hereby declare the following to be a full, clear, and exact description of the invention, such as will enable others skilled in the art to which it pertains to make and use the same.

This invention relates to new and useful improvements in reels, and particularly to clothes line reels.

One object of my invention is to provide a reel of the character indicated which will be light in weight, which will be durable and which can be cheaply produced.

A further object of my invention is to provide a reel having improved means for manipulating the same whereby the line may be wound or unreeled therefrom without applying the hands directly to the line, thereby eliminating any danger of injury to the hands of user when putting out or taking in the line.

Another object of my invention is to provide an improved reel which will be very compact in construction thereby permitting the reel together with the line to be stored in a very small space.

Other objects of this invention will appear in the following description, reference being had to the accompanying drawings wherein Fig. 1 is a view in elevation of a reel embodying my invention. Fig. 2 is a section on line 2—2 Fig. 1.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

By referring to the drawing it will be seen that my reel comprises two conoidal or dish shaped members each having a base portion 10 and an annular inclined flange portion 11.

In practice these members may preferably be formed from stampings. The said members are placed together in oppositely disposed positions, so that the bottoms of the base portions abut against each other. Each

member is provided with a centrally located circular opening 12 and when the members are placed together the said openings register with each other. In each base portion 10 at diametrically opposite sides are formed slots 13 and on said base portion intermediate of said slots are formed tongues 14.

When the two members are placed together the tongues on one member pass through the slots in the other member and the tongues on the last member pass through the slots in the first mentioned member. The tongues 14 are made sufficiently long so that they extend beyond the faces of said base portions 10 and are then bent down and clinched against said faces, rigidly securing the said members together.

When the said members are thus secured together it will be readily seen that the base portions 10 constitute the hub of my reel, which will be quite strong and rigid as it comprises two thicknesses of sheet metal. The cooperating inclined flange portions 11, form an annular V-shaped sheave portion for receiving the wash line.

On one face of the hub of the reel is rigidly secured a handle in the form of a bail, shown at 16. In the bail 16 is formed a circular opening 17 in line with the central opening in the hub. A pin or stud shaft 18 is passed through the opening 17 in the bail 16 and through the central opening in the hub and projects beyond the opposite face of the hub. On the projecting end of said pin is mounted a handle 19, which is thus mounted so as to permit the reel to be rotated relatively thereto. A washer 20 is preferably interposed between the face of the hub and the end of the handle 19.

It will be noted that the sheet metal base portion or face 10 of each reel half or section is flat throughout its extent and that the faces of these two sections are therefore juxtaposed throughout, so that when the bail 16 is attached to the space of one section it will lie entirely in the hollow space formed by such dish-shaped section. As a result the handle or bail will not project out beyond the plane of the outer edge of the section and hence the reel can lie flatwise upon the floor.

A key hole slot 21 is formed in one of the flanges 11 into which the end of the line may be inserted preparatory to winding the line on the reel.

The operation of my reel will be readily

understood. When it is desired to wind or coil the line on the reel, the end of the line is inserted in the key hole slot 21. The device may then be grasped by the bail 16 and held rigid in one hand while the line is coiled on the reel with the other hand. However, if the line be rough it will be preferable to hold the device by the handle 19 and then revolve the reel by twirling the bail 16. In this way the line can be tightly coiled without touching it with the hands. The V-shaped sheave groove causes the line to feed on to the reel in compact even layers so that a long line can be coiled on a reel of comparatively small diameter.

When it is desired to unwind or pay out the line, it is only necessary to hold the device by the handle 19 while walking from line support to line support and the pull on the line will cause the reel to rotate freely and pay out the line as desired. When it is necessary to draw the line taut, the device may be grasped by the bail 16 which of course stops the rotation of the reel and then any tension desired may be exerted on the line.

It is to be understood that by describing in detail herein any particular form, structure or arrangement, it is not intended to limit the invention beyond the terms of the several claims or the requirements of the prior art.

What I claim is:

1. A reel comprising a V-shaped sheave portion terminating at the apex thereof in a relatively flat hub portion located intermediate the planes of the outer sheave edges, and a pair of handles extending one transversely to the other, one of said handles adapted to be manipulated for rotating the reel and the other handle pivotally secured to the hub to permit said reel to be rotated.

2. A clothes line reel comprising a pair of dish-shaped sections connected together base to base and a handle having one end secured to the base of a section and the other end located within the plane of the outer edge of said dish shaped section.

3. A clothes line reel comprising a pair of members, having flat base portions juxtaposed and connected together, said members forming a V-shaped sheave portion, and a bail connected to the base portion of one of said members, and located within the plane of the outer edge of said member.

4. A clothes line reel comprising two members, each member consisting of a base portion and an inclined annular flange portion, said members being oppositely disposed with their bases abutting, means for securing the base portions of said members together, a bail rigidly secured to the face of the base portion of one of said members and a handle rotatably mounted on the face of the base portion of the other member.

5. A clothes line reel comprising a hub portion, a sheave portion, a bail rigidly mounted on one side of the hub portion, a pin having a bearing in said bail and extending centrally through said hub portion and a handle mounted on said pin.

6. A clothes line reel comprising a hub portion, a sheave portion, a handle pivotally mounted at one side of said hub portion at the axis thereof whereby the reel can be rotated relatively to said handle, and a second handle rigidly mounted at the opposite side of said hub.

7. A clothes line reel comprising a pair of dish-shaped sections connected together base to base and forming a V-shaped sheave portion, and a pair of handles, one rigidly secured to the reel and one rotatably connected thereto.

8. A clothes line reel comprising a pair of dish-shaped sections connected together base to base and forming a V-shaped sheave portion, and a pair of interconnected handles, one rigidly secured to the reel and one rotatably connected thereto.

9. A clothes line reel comprising a pair of dish-shaped sections connected together base to base and forming a V-shaped sheave portion, and a pair of handles connected at opposite sides of the reel, one of said handles being rigidly secured to the reel and one rotatably connected to the reel.

10. A clothes line reel comprising a pair of sheet metal disk-shaped sections having flat bases connected together and juxtaposed, said sections forming an annular V-shaped sheave portion, and a handle located entirely within one section.

In testimony whereof, I sign the foregoing specification, in the presence of two witnesses.

GEORGE J. LEBER.
